(57) CLAIM

The ornamental design for a packaging case, as shown and described.

DESCRIPTION

FIG. 1 is a perspective view of a first embodiment of a packaging case showing my new design;

FIG. 2 is a front view thereof, the rear view being a mirror image of FIG. 2;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof with a lid in an open position;

FIG. 8 is a top plan view thereof with the lid in an open position;

FIG. 9 is a perspective view of a second embodiment of a packaging case showing my new design;

FIG. 10 is a front view thereof, the rear view being a mirror image of FIG. 10;

FIG. 11 is a top plan view thereof;

FIG. 12 is a bottom plan view thereof;

FIG. 13 is a right side view thereof;

FIG. 14 is a left side view thereof;

FIG. 15 is a perspective view thereof with a lid in an open position; and,

FIG. 16 is a top plan view thereof with the lid in an open position.
